PROTECTIVE GARMENT

Virginia H. Chadwick, Louisville, Ky., assignor to
 Earnshaw Knitting Company, Newton, Mass.,
 a corporation of Massachusetts

Application August 16, 1940, Serial No. 352,901

2 Claims. (Cl. 2—46)

This invention relates to protective garments and more particularly to a protective cape or bib for mothers and other persons feeding infants with a bottle.

Mothers everywhere frequently voice their annoyance at having their dress soiled by milk and other liquid foods ejected or driveling from the mouth of a bottle-fed infant. Milk thus spilled on a mother's dress furthermore has a very offensive odor, particularly after the milk has dried on the dress. While some mothers endure the damp and smelly consequences of feeding an infant simply because special protective garments are unknown, more fastidious mothers have taken to such expediencies as draping a clean absorbent diaper over a shoulder, not only for the purpose of protecting their dress from all matter belched or driveling from the infant's mouth but also for protecting the infant against all germs infesting the mother's dress. However, this practice is unsatisfactory and oftentimes annoying in that a diaper thus draped over a shoulder not only interferes with the free use of the arm but becomes easily disarranged and falls off at the slightest provocation.

It is the aim and object of the present invention to provide for mothers and other infant-attending persons a protective cape or bib of absorbing cloth which effectively protects the dress against the messy and odorous consequences of infant-feeding and drooling and is easily put on or removed and which does not become readily disarranged through the use of the arms nor slips off on its own accord.

Before explaining in detail the present invention it is to be understood that the invention is not limited in its application to the details of construction and arrangement of parts illustrated in the accompanying drawing, since the invention is capable of other embodiments and of being practiced or carried out in various ways. Also it is to be understood that the phraseology or terminology employed herein is for the purpose of description and not of limitation and it is not intended to limit the invention claimed herein beyond the requirements of the prior art.

In the drawing:

Fig. 1 illustrates the novel bib laid out flat.

Fig. 2 illustrates a person wearing the bib while feeding an infant with a bottle.

Fig. 3 illustrates a person wearing the bib while holding an infant after a feeding.

Fig. 4 illustrates a modified bib.

Fig. 5 is a section taken on the line 5—5 of Fig. 4.

Referring to Fig. 1, the reference numeral 10 designates a bib which consists of two outer layers 11 and 12 of a textile fabric and an intermediate layer 13 of any suitable absorbent cloth. These layers 11, 12 and 13 are joined along their edges by stitches 14. The bib is preferably shaped in the fashion shown in Fig. 1 when laid out flat, and comprises a breast flap 15 and two identical back flaps or lobes 16 on opposite sides of a round neck cutout 17. The flaps 15 and 16 have complementary shoulder portions 18 which are joined by stitches 19.

The breadth of the breast flap 15 is such as to substantially cover the breast of the person wearing the bib (see Fig. 2) and the shoulder portions 18 are of a spread substantially equal to the breadth of the person's shoulders. To prevent disarrangement of the breast flap 15 by the arms of the person wearing the bib while attending an infant as shown in Figs. 2 and 3, for instance, the side edges 20 of said flap 15 gradually recede inwardly at a smooth curvature toward, and merge with, the outer edges of the narrower shoulder portions 18. Furthermore, the lower portion of the breast flap 15 has a substantially V-shaped cutout 21 in the center which leaves disjointed flap ends 22 and in a sense divides said flap 15 into two lobes. The disjointed flap ends permit some disarrangement of part of the breast flap by the wearer's arm, for instance, without disarranging the remaining part of said flap.

The back flaps or lobes 16, when brought together at their adjacent edges 23 by tying the bands 24 of the bib at the back of a person's neck, for instance, are preferably substantially congruent to the breast flap 15 so that the bib may be worn in another fashion, i. e., such that the back flaps 16 cover a person's breast while the breast flap 15 covers the person's back. Thus, when the breast flap 15 has become soiled after several feedings and the back flaps 16 have remained clean, the bib may be used further in the other fashion mentioned before washing the bib. If desired, the bib may even be worn inside out before it is washed, thus obtaining maximum service out of a bib before it needs washing. The various lobes of the bib are rounded as shown at 25 and 25a for the purpose of minimizing the chances of rolling up the edges of the bib by the arms of the person wearing it in any fashion and assuring the free suspension of these lobes at all time.

The back flaps or lobes 16, when suspended on a person's back, effectively prevent a general

displacement of the protective flap 15 on the person's breast, as will be readily understood. On the other hand, the division of the breast flap 15 by the V-shaped cutout 21 into two partly disjointed lobes and the inwardly receding outer edges 20 of said lobes as well as the restricted breadth of the shoulder portions 18 contribute toward preventing, or at least localizing, the disarrangement of any part of the breast flap 15 by the arms of a person wearing the bib. Moreover, the flaps 15 and 16 are made just sufficiently long to effectively protect the relatively restricted breast area against which an infant rests while being held during bottle feeding in the conventional and medically approved way shown in Fig. 2. Thus, the relatively short flaps of the bib will never be disarranged if the person wearing it sits down or gets up. The back flaps or lobes 16, moreover, protect the back from all matter belched or driveling from an infant's mouth where the head of the infant is placed on a person's shoulder after a feeding, as shown in Fig. 3.

The bib is furthermore so fashioned that it may be laid out absolutely flat in the manner shown in Fig. 1, thereby greatly facilitating the washing and ironing of the same.

The modified bib shown in Fig. 4 has the same breast flap 15 as the bib shown in Fig. 1, but the back flap 16a is in one piece and not parted like the back flaps 16 of the bib in Fig. 1. To facilitate putting on the bib, the back flap 16a is centrally longitudinally parted for some distance at the neck cutout as shown at 30. Bands 31 or any other expedient means may be used to tie the bib behind the person's neck. In order that the sloping shoulders of the person wearing the bib may not interfere with the uniform suspension of the flaps 15 and 16a from the person's shoulders, the shoulder portions 18a are raised toward the neck opening 17a as shown in Fig. 5.

After the bib is of no further use to a mother as a protective cover for herself, it may then be used

as a regular bib for an older child which is past the "bottle stage."

I claim:

- 5 1. A bib for an infant-attending person having a neck opening sufficiently large to be unaffected by any motion of the person's head, two shoulder covers disposed at opposite sides of said opening and having substantially the same spread as the person's shoulders, and front and back covers depending from opposite sides, respectively, of said shoulder covers, said front cover having its lower portion in form of two rounded and slightly outwardly flaring flaps which substantially cover the person's breasts but do not materially extend therebeyond and are partially parted from each other by a V-shaped notch in the lower edge, the outer surface of said front cover being uninterrupted to provide a smooth uniform surface and the side edges of said flaps merging gradually into the outer edges of said shoulder covers.
- 10 2. A bib for an infant-attending person having a neck opening sufficiently large to be unaffected by any motion of the person's head, two shoulder covers disposed at opposite sides of said opening and having substantially the same spread as the person's shoulders, substantially congruent front and back covers depending from opposite sides, respectively, of said shoulder covers, said front cover having its lower portion in form of two rounded and slightly outwardly flaring flaps which substantially cover the person's breasts but do not materially extend therebeyond and are partially parted from each other by a relatively deep V-shaped notch in the lower edge, the outer surface of said front cover being uninterrupted to provide a smooth uniform surface and the side edges of said flaps merging gradually into the outer edges of said shoulder covers.
- 15 3. A bib for an infant-attending person having a neck opening sufficiently large to be unaffected by any motion of the person's head, two shoulder covers disposed at opposite sides of said opening and having substantially the same spread as the person's shoulders, substantially congruent front and back covers depending from opposite sides, respectively, of said shoulder covers, said front cover having its lower portion in form of two rounded and slightly outwardly flaring flaps which substantially cover the person's breasts but do not materially extend therebeyond and are partially parted from each other by a relatively deep V-shaped notch in the lower edge, the outer surface of said front cover being uninterrupted to provide a smooth uniform surface and the side edges of said flaps merging gradually into the outer edges of said shoulder covers, and said back cover being centrally parted throughout its length, and releasable joining means provided on the parted sections of the back cover near the neck opening.
- 20 4. A bib for an infant-attending person having a neck opening sufficiently large to be unaffected by any motion of the person's head, two shoulder covers disposed at opposite sides of said opening and having substantially the same spread as the person's shoulders, substantially congruent front and back covers depending from opposite sides, respectively, of said shoulder covers, said front cover having its lower portion in form of two rounded and slightly outwardly flaring flaps which substantially cover the person's breasts but do not materially extend therebeyond and are partially parted from each other by a relatively deep V-shaped notch in the lower edge, the outer surface of said front cover being uninterrupted to provide a smooth uniform surface and the side edges of said flaps merging gradually into the outer edges of said shoulder covers, and said back cover being centrally parted throughout its length, and releasable joining means provided on the parted sections of the back cover near the neck opening.
- 25 5. A bib for an infant-attending person having a neck opening sufficiently large to be unaffected by any motion of the person's head, two shoulder covers disposed at opposite sides of said opening and having substantially the same spread as the person's shoulders, substantially congruent front and back covers depending from opposite sides, respectively, of said shoulder covers, said front cover having its lower portion in form of two rounded and slightly outwardly flaring flaps which substantially cover the person's breasts but do not materially extend therebeyond and are partially parted from each other by a relatively deep V-shaped notch in the lower edge, the outer surface of said front cover being uninterrupted to provide a smooth uniform surface and the side edges of said flaps merging gradually into the outer edges of said shoulder covers, and said back cover being centrally parted throughout its length, and releasable joining means provided on the parted sections of the back cover near the neck opening.
- 30 6. A bib for an infant-attending person having a neck opening sufficiently large to be unaffected by any motion of the person's head, two shoulder covers disposed at opposite sides of said opening and having substantially the same spread as the person's shoulders, substantially congruent front and back covers depending from opposite sides, respectively, of said shoulder covers, said front cover having its lower portion in form of two rounded and slightly outwardly flaring flaps which substantially cover the person's breasts but do not materially extend therebeyond and are partially parted from each other by a relatively deep V-shaped notch in the lower edge, the outer surface of said front cover being uninterrupted to provide a smooth uniform surface and the side edges of said flaps merging gradually into the outer edges of said shoulder covers, and said back cover being centrally parted throughout its length, and releasable joining means provided on the parted sections of the back cover near the neck opening.
- 35 7. A bib for an infant-attending person having a neck opening sufficiently large to be unaffected by any motion of the person's head, two shoulder covers disposed at opposite sides of said opening and having substantially the same spread as the person's shoulders, substantially congruent front and back covers depending from opposite sides, respectively, of said shoulder covers, said front cover having its lower portion in form of two rounded and slightly outwardly flaring flaps which substantially cover the person's breasts but do not materially extend therebeyond and are partially parted from each other by a relatively deep V-shaped notch in the lower edge, the outer surface of said front cover being uninterrupted to provide a smooth uniform surface and the side edges of said flaps merging gradually into the outer edges of said shoulder covers, and said back cover being centrally parted throughout its length, and releasable joining means provided on the parted sections of the back cover near the neck opening.
- 40 8. A bib for an infant-attending person having a neck opening sufficiently large to be unaffected by any motion of the person's head, two shoulder covers disposed at opposite sides of said opening and having substantially the same spread as the person's shoulders, substantially congruent front and back covers depending from opposite sides, respectively, of said shoulder covers, said front cover having its lower portion in form of two rounded and slightly outwardly flaring flaps which substantially cover the person's breasts but do not materially extend therebeyond and are partially parted from each other by a relatively deep V-shaped notch in the lower edge, the outer surface of said front cover being uninterrupted to provide a smooth uniform surface and the side edges of said flaps merging gradually into the outer edges of said shoulder covers, and said back cover being centrally parted throughout its length, and releasable joining means provided on the parted sections of the back cover near the neck opening.
